UNITED STATES PATENT OFFICE

BRADFORD E. STEPHENS, OF NEEDHAM, MASSACHUSETTS

PAMPHLET AND BOOK COVER

Application filed December 31, 1930. Serial No. 505,681.

This invention relates to improvements in covers or protectors for periodicals, booklets, pamphlets or the like, and the principal object of the invention is to provide a simple and inexpensive cover which will protect the paper contents against dust, wear or soilage. Further objects reside in the structural features of the protector hereinafter described and pointed out in the appended claims.

10 A recommended embodiment of the invention is illustrated in the accompanying drawing which show a cover adapted particularly for enclosing a bound periodical. It will be understood, however, that any desired collection of sheets, either bound or loosely assembled may be suitably secured within the protector; and that the size, shape and structural details of the protector may be varied to suit particular purposes. In the drawing:

20 Fig. 1 is a perspective view of the improved cover in closed position;

Fig. 2 is an enlarged section taken on line 2-2 of Fig. 1 and showing the cover partially opened;

25 Fig. 3 is a plan view of a blank suitable for making the cover; and

Fig. 4 is a plan view of the opened cover with the contents removed.

The improved cover is preferably made of 30 cardboard, heavy paper, or other relatively stiff sheet material and is preferably formed in one piece from a blank of the material cut as shown in Fig. 3. The blank is folded along parallel lines 6 to provide similar side 35 portions 7 and a back 8, the fold-lines 6 constituting the hinges of the cover and the back portion 8 being sufficiently wide to accommodate the periodical or booklet which is to be fastened therewithin.

40 The projecting side wings 9 and end wings 10 of each side portion 7 are folded inwardly on spaced parallel lines to provide outer edge walls 11 and 12 at the sides and ends of the sides 7, and rearwardly inclined portions 45 which are cemented or otherwise fastened to

the inner surface of the cover as at 13 and 14 respectively. The edge walls 11 and 12 meet at the corners of the protector, and flat ledges 15 and 16 are preferably formed in the folded wings at right angles to said walls, thus furnishing marginal ribs or flanges of substantial thickness and rigidity. Hence the ledges 15 and 16 of the respective sides meet each other when the cover is closed over its contents, thereby providing a neat, compact, 50 and dust proof protector which may be quickly opened to permit inspection of the reading matter enclosed therewithin.

The sheets, pamphlets or periodical 17 may be stitched or otherwise secured within the folding cover in any appropriate arrangement. For example, a bound pamphlet may be fastened by stitching 18 to a backing strip or reinforcement 19 adhesively united to the inner face of the cover back 8. The periphery of the booklet 17 lies within the border 60 formed by the marginal flanges 9 and 10 which close together as aforesaid to protect the contents of the cover from dirt or wear.

From the foregoing it is evident that I 70 have provided a compact and efficient protector which is easy and economical to manufacture, durable in use, and pleasing in appearance. The outer surfaces of the cover may be ornamented or inscribed as desired 75 in case the cover is to be used repeatedly for a particular periodical; yet it will be apparent that the low cost of the cover permits it to be frequently replaced if necessary.

I claim:

1. A protective cover for periodicals or the like, comprising a folded sheet having integral back and side portions, means to secure the periodical to the back portion and the side portions folding to closed position 85 at opposite sides of the periodical, and each of said side portions having integral peripheral flanges bent inwardly thereof, the flanges of the respective portions meeting in edge-to-edge relation when the sides are folded to 90

gether, thereby to enclose the contents of the cover.

2. A protective cover for periodicals or the like, comprising back and side portions formed of a single sheet of material, means to secure the periodical to the back portion and the side portions folding relatively to the back toward opposite sides of the periodical, each side portion having its margins folded inwardly to provide upstanding flanges having substantially flat ledges, the ledges of the respective flanges abutting each other when the sides are folded together, thereby to enclose the contents of the cover.

15 In testimony whereof I affix my signature.

BRADFORD E. STEPHENS.
